UNITED STATES PATENT OFFICE.

HARRY ALLEN, OF SAVANNAH, GEORGIA.

WRENCH.

1,132,146.

Specification of Letters Patent. Patented Mar. 16, 1915.

Application filed April 6, 1912. Serial No. 688,948.

To all whom it may concern:

Be it known that I, HARRY ALLEN, a citizen of the United States, residing at Savannah, in the county of Chatham and State of Georgia, have invented new and useful Improvements in Wrenches, of which the following is a specification.

This invention relates to wrenches and particularly to a pipe wrench, the object of 10 the invention being to provide a wrench which may be used upon highly polished pipes without marring their polished surfaces.

In pipe wrenches it is customary to 15 vide steel toothed jaws for their effective gripping engagement upon the pipe. These jaws, while being entirely satisfactory for effecting their desired purchase upon the pipe are extremely objectionable in that 20 highly polished nickel or brass pipes are severely marred or scratched.

It is, therefore, a particular object of the invention to provide a wrench wherein the jaws thereof are formed of soft metal such 25 as lead which may be engaged with the maximum friction against the pipe and operated thereon without scratching or marring the pipe.

Another object of the invention is to 30 provide a wrench in which the soft metal liners of the jaws can be readily removed when worn and replaced by new liners at a very small cost.

In the drawing, forming a portion of this 35 specification and in which like numerals of reference indicate similar parts in the several views: Figure 1 is a longitudinal section through the wrench. Fig. 2 is an edge view thereof. Fig. 3 is a section on line 40 3—3 of Fig. 1. Fig. 4 is a perspective view of one of the liners. Fig. 5 is a perspective view of the liner retaining key.

The wrench herein shown preferably includes a handle or stock 1 which terminates 45 at one end in spaced walls 2 and a fixed jaw 3. The movable jaw 4 is provided with an arcuate shank 5 which is pivoted, at 6, between the walls 2 of the stock and at one side of the pivot 6, the shank 5 is pivoted, 50 at 7, to one end of the actuating rod 8. The stock 1 is preferably hollow, and as shown, the actuating rod 8 is slidable in the stock and interposed between one end of the stock and the stop 9 of the rod 8 is a helical extensible spring 10 which is adapted to exert 55 its force against the rod 8 so that the jaw 4

is normally held closed against the fixed jaw 3. A controlling lever 11 is pivoted, at 12, between the walls 2 of the stock of the wrench. This lever is provided with a 60 portion 13 which is operatively associated with the rod 8 so that when the lever is actuated manually the jaw 4 can be moved to an open position to facilitate the attachment of the wrench to the pipe.

Each jaw of the wrench is provided with a concavity 14, the walls of the concavity of one jaw being arranged in opposing relation to the walls in the concavity of the opposite jaw, and as illustrated, the walls 70 of one jaw are substantially eccentrically arranged with relation to the walls of the other jaw.

Each of the jaws are provided with a transversely disposed passage 14' and having communicating therewith at a point medially of their length and at right angles thereto a radial passage 15, the latter mentioned passage receives the lug 16 of a soft metal liner 17, the latter being of a concavo-convex configuration, the convexity of 80 which conforms with the concavity of the jaw as shown. The jaw is provided with a retaining wedge key 18, said key being inserted in one end of the transverse passage 85 14' until the same tightly binds or engages with the walls thereof, the said key being passed through the elongated slot 19, which is of a diameter less than the diameter of the passage 14', and upon the longitudinal 90 movement of the key through the passage 14', the same will be brought to bear against the wall 21 of the slot 19 so as to effect the adjustment of the liner and the jaw to thereby insure the positive frictional engagement of the former with the latter and preventing any accidental rotation of the 95 key 18 in the slot 19 or the passage 14'.

At one end the wedge key is provided with a head 22. At the opposite end, the 100 key is provided with an integral threaded portion 23 on which is adjustably mounted a retaining nut 24. The adjusting nut is capable of movement on the portion 23 so as to cause the latter to operatively move 105 in the jaw against the wall 21 of the slot 19 to effect the positive adjustment of the liner, as stated. The liner 17 is preferably constructed of lead, but it is understood that any suitable soft metal may be substituted 110 therefor. In practice, it has been found that lead liners upon wrench jaws posi-

tively eliminate the scratching of highly polished pipes and it has further been found that such soft metal liners are an effective substitute for the hard steel toothed jaws commonly used on well known forms of pipe wrenches.

By reference to Fig. 1 of the drawing, it will be noted that the concaved working face of the jaw 5 is of a materially greater length than that of the jaw 3, and also that each of the liners is of a length approximately equaling the length of the jaw upon which it is arranged. This is a highly desirable, if not essential, feature, because such an arrangement provides for a comparatively large amount of adjustment between the liners and jaws, and also the arrangement permits of the liners engaging with polished pipes of varying cross sectional diameters.

I claim:

In a wrench for use on polished pipes, the combination with a stock having a fixed jaw provided with an incurved face, a pivoted jaw also provided with an incurved

face arranged opposite the incurved face of the fixed jaw, the said face of the pivoted jaw being of a greater length than that of the fixed jaw, said jaws each having an opening arranged at a right angle to the axial longitudinal plane of the curved faces and central of each of the jaws, and being further provided with a wedge-shaped opening arranged transversely of the first mentioned opening, of a segmental liner for each of the incurved faces of the jaws, each of said liners having a central outturned lug which is adapted to be received each within one of the openings of the jaws, each of said lugs having an elongated slot, and a wedge-shaped key passing through each of the transverse openings in the jaws and through the openings in the lugs for sustaining the liners upon the jaws.

In testimony whereof I affix my signature in presence of two witnesses.

HARRY ALLEN.
